UNITED STATES PATENT OFFICE.

GEORGE W. JACOBS, OF LOS ANGELES, CALIFORNIA.

CAR COUPLER.

Application filed June 13, 1922. Serial No. 567,955.

To all whom it may concern:

Be it known that I, GEORGE W. JACOBS, a citizen of the United States, residing at Los Angeles, in the county of Los Angeles and 5 State of California, have invented new and useful Improvements in Car Couplers, of which the following is a specification.

One object of my said invention is the provision in a car coupler of automatic type of 10 simple and inexpensive means for assuring the coupler jaw assuming an open position when cars are moved apart, thereby assuring proper operation of the jaw and an effective coupling when cars come together 15 and this in such manner as to obviate the necessity of a trainman going between cars in order to open or correctly position for coupling the jaw of the coupler.

Another object of the invention is the provision of improved means for the purpose indicated in the form of an attachment 20 readily applicable to automatic couplers such as at present in general use.

To the attainment of the foregoing, the 25 invention consists in the improvement as hereinafter described and definitely claimed.

In the accompanying drawings, forming part of this specification:—

Figure 1 is a plan view showing as connected two couplers constructed in accordance with my invention.

Figure 2 is a plan view of one coupler with the jaw in open position.

Figure 3 is a side elevation of the same.

Figure 4 is a side elevation of a coupler as it appears with the jaw in closed position.

Figure 5 is a detail elevation showing the pin and spring comprised in my improvement.

Figure 6 is a fragmentary inverted plan.

Similar numerals of reference designate corresponding parts in all of the views of the drawings.

Figure 1 clearly illustrates that couplers constructed in accordance with my invention are adapted to be connected together in the strong and safe manner common to automatic couplers.

My novel couplers are identical in construction and therefore a detailed description of the coupler shown in Figures 2 to 6 will suffice to impart a definite understanding of all. The coupler referred to includes a drawhead 1, a jaw 2, a pin 3 pivotally connecting the jaw 2 to the drawhead, and a

spring 4 for assuring movement of the jaw 2 to the open position immediately following the raising of the locking pin 5 of the coupler, and the drawing of two couplers 60 apart. In the drawhead 1 is provided an opening 6, Figure 3, to receive the pin 3, and at the underside of the drawhead 1 and surrounding the said opening 6 is a boss 7, immediately below which is a supplemental 65 boss 8, Figures 3, 4 and 6, the said supplemental boss 8 having radial grooves 9 which extend throughout its depth. Said supplemental boss 8 may be and preferably is integral with the boss 7. The jaw 2 is of conventional configuration and is provided in one of its arms with an opening 10 to receive the pin 5, and in its other arm with an opening 11. The pin 3 is disposed in the drawhead 1, and is locked against turning in the 70 drawhead through the medium of a cotter pin 12, best shown in Figures 3 and 6, which cotter pin extends through a diametrical aperture in the pin 3, and is seated in alined grooves 9 of the supplemental boss 8. The 75 spring 4 is provided with an arm 13 which extends through an aperture in the upper portion of the pin 3, and in virtue of the said cotter pin 12 in combination with the grooved supplemental boss 8, the pin may be 80 adjustably positioned and fixed so as to correctly tension the spring 4 as different conditions require. In addition to the terminal arm 13 the spring 4 includes convolutions 85 14, an arm 15 and a pendent loop 16 on said arm 15, the said pendent loop 16 being designed to be socketed in the jaw opening 11 as clearly shown in Figures 2 and 3. Manifestly when so socketed the loop 16 will be compressed, see dotted lines in Figure 3, 90 and hence it will tend to retain itself by frictional contact in the jaw 2.

It will be apparent from the foregoing that my novel construction absolutely obviates the necessity of a trainman incurring 100 the danger incident to going between two cars, the spring 4 operating efficiently to move the jaw 2 to the open position shown in Figure 2 just as soon as the pin 5 is lifted and the cars moved apart. It will also 105 be apparent that the improved appurtenances are simple and inexpensive, and that therefore, the improvement is adapted to be readily embraced in couplers such as at present in use.

I have entered into a detailed description of the construction and relative arrange-

ment of the parts embraced in the present and preferred embodiment of my invention in order to impart a full, clear and exact understanding of the said embodiment. I do not desire, however, to be understood as confining myself to the specific construction and relative arrangement of parts inasmuch as in the future practice of the invention various changes and modifications may be made such as fall within the scope of my invention as defined in my appended claim.

Having described my invention, what I claim and desire to secure by Letters Patent, is:—

15 In combination, a draw head formed with a vertical pin receiving opening, a jaw member, a pivot pin extending through an opening in the jaw member, and the pin receiving opening of the draw head for pivotally connecting the jaw member thereto, said draw head being formed at one side with a plurality of slots adjacent the pin receiving opening and extending radially there-

from, a cotter pin extending through the transverse opening in the pivot pin and seating in one of said radial slots, a coil spring having one end formed in diametrical relation to the coil thereof, and extending through an opening in the end of the pin opposite the end receiving the cotter pin, said end portion seating against the surface of the draw head, and the other end of said spring extending outwardly from the coil and formed with a laterally extending terminal seating in an opening in the jaw member, whereby the cotter pin secures the pivot pin against axial movement in the draw head, locks the diametrical end portion of the spring in the pin against the upper side of the draw head, and is adapted for adjustment in the radial slots to increase or decrease the tension of the spring for operating the jaw member.

In testimony whereof, I affix my signature.

GEORGE W. JACOBS.
